(57) **CLAIM**

The ornamental design for a barbecue implement with laminated grip, as shown and described.

DESCRIPTION

FIG. 1 is a front elevational view of a barbecue implement with laminated grip showing my new design;

FIG. 2 is a left side view thereof;

FIG. 3 is a right side view thereof;

FIG. 4 is a bottom view thereof; and,

FIG. 5 is a top plan view thereof.

The rear elevation is a mirror image of the front elevation illustrated in FIG. 1 and the broken line showings form no part of the claimed design.
